UNITED STATES PATENT OFFICE.

ALBERT E. DERUS, OF CHICAGO, ILLINOIS.

DESIGN FOR A VENDING-MACHINE CASING.

Application filed October 27, 1925. Serial No. 15,268. Term of patent 7 years.

To all whom it may concern:

Be it known that I, ALBERT E. DERUS, a citizen of the United States, residing at Chicago, in the county of Cook and State of Illinois, have invented a new, original, and ornamental Design for a Vending-Machine Casing, of which the following is a specification, reference being had to the accompanying drawing, in which—

Figure 1 is a front elevation of the vending machine casing, showing my new design, and Figure 2 is a side elevation thereof.

I claim:—

The ornamental design for a vending-machine casing, as shown.

In testimony whereof I affix my signature.

ALBERT E. DERUS.
